UNITED STATES PATENT OFFICE.

WILLIAM W. LORD, OF RACINE, WISCONSIN.

DESIGN FOR A PAPER-WEIGHT.

SPECIFICATION forming part of Design No. 12,429, dated August 23, 1881.

Application filed July 18, 1881. Term of patent 3½ years.

To all whom it may concern:

Be it known that I, WM. W. LORD, a citizen of the United States, residing at Racine, in the county of Racine and State of Wisconsin, have invented and produced a new and original Design for Paper-Weights, of which the following is a specification, reference being had to the accompanying photograph, forming part thereof.

10 The photograph is a view of the upper surface of my newly-designed weight, one view of which is deemed sufficient to fully illustrate my design.

My design consists in a medallion, *a*, raised

15 on the upper surface of the weight *b*, representing a human face in death, with an expression of suffering, together with the sentence "Talked to death," or other words of like import, the whole to be molded or cast in any metal suitable for a paper-weight. 20

I claim—

The design for a paper-weight herein shown and described, the same consisting in the raised medallion *a* on the upper surface of the weight *b*, with the words "Talked to death."

Witnesses: WM. W. LORD.
